UNITED STATES PATENT OFFICE

WILLIS F. HUDSON, OF RIVERSIDE, ILLINOIS, ASSIGNOR TO THE HOOVER COMPANY, A CORPORATION OF OHIO

SUCTION CLEANER AGITATOR

Application filed November 6, 1929. Serial No. 405,091.

The present invention relates to suction cleaners and more particularly to suction cleaner agitators of the rotary type. The art of carpet cleaning has advanced from the stage represented by the old fashioned carpet cleaner with its wheel-driven brush rotating in contact with the surface covering and performing in a primitive fashion the cleaning function desired, to a stage characterized by positive agitation within a suction nozzle through which air is drawn at high velocity. The inclusion in the modern cleaner of the positive agitator and high vacuum has resulted in a decrease in the effectiveness of the sweeping brush, when included in the combination, until finally the brush may well be done away with and the dislodgment of the foreign matter in the surface covering left entirely to the positive beating element of the agitator. It is toward an agitator for suction cleaners totally devoid of the usual brush sweeping means that the present invention is directed.

It is the object of the present invention to provide a suction cleaner agitator of simple construction, durable and efficient. It is a further object of the present invention to provide a suction cleaner agitator in which the usual body portion has been omitted. A further object is the provision of a rotor in which the beating elements comprise the only body portion. Other and more specific objects will appear upon reading the specification and taking into consideration the drawing annexed thereto.

Referring to the drawing:

Figure 1 is a side view of an agitator constructed in accordance with the present invention;

Figure 2 is a cross section upon the line 2—2 of Figure 1;

Figure 3 is a cross section of the construction shown in Figure 1 upon the line 3—3;

Figure 4 is a disclosure of a modified embodiment of the present invention;

Figure 5 is a cross section upon the line 5—5 of Figure 4.

The present invention, which is characterized by its extreme simplicity, comprises, as shown in Figures 1, 2 and 3, end plates 1 and

2 which are connected at diametrically opposite points by the beater bars 4, 4 which extend helically therebetween upon the surface of an imaginary cylinder of the same diameter as the end plates 1 and 2. Beater bars 4, 4 are preferably circular in cross section, of metal, and of sufficient diameter so that they possess the rigidity and strength requisite to prevent their distortion either by bending or twisting. End plate 2 is of considerable greater width than plate 1 and is provided with a grooved portion 5 which forms a pulley for the driving belt, the portion 5 being sufficiently grooved so that the belt will not extend beyond the outer surface of the end plate when in position. Supporting shafts 6 and 7 are carried by end plates 1 and 2 respectively which extend perpendicularly therefrom and are adapted to be seated in a bearing of any suitable design in order that the agitator may be rotatably mounted in a suction cleaner. The mounting for the agitator in the bearing forms no part of the present invention.

Referring now to Figure 4 in particular, a modified form of the present invention is shown in which the end plate 2 is of the same width as end plate 1 and a separate pulley member is provided therebetween which is indicated by the reference character 8. In the present modification the beater bars 4, 4 are formed with a V-shaped inwardly deflected portion intermediate their ends and in the assembled relation of the agitator the pulley 8, which also has a V-shaped cross section, is seated within the V-shaped portions of the bars 4, 4 and secured in some suitable manner as by welding. The pulley 8 is preferably positioned relative to the bars 4, 4 before said bars are permanently attached to the end plates. Stub-shafts 6 and 7 fixedly carried by end plates 1 and 2, as in the first modification, provide means whereby the agitator may be rotatably mounted in a suitable bearing.

An agitator constructed in accordance with the present invention is adapted to be positioned within the suction cleaner nozzle and connected to the driving motor through a belt drive. In the operation of the cleaner the suction within the suction nozzle func-

tions to raise the surface covering against the lips of the nozzle containing the agitator and the beater bars 4, 4, which are rotated at high speed by the driving motor through the 5 driving belt, contact the uplifted surface covering and impart thereto a vibratory motion through repeated impacts. The foreign matter lodged within the surface covering is dislodged by the impacts of the beater bars and 10 the cleaning air entering the suction nozzle carries it away to the dust receptacle. The operation of the specific agitator is the same as the agitator now in common use and no claim is made to the method of cleaning a surface covering but what is claimed as the applicant's invention is an improved and simplified agitator construction which is characterized by its simplicity, durability and efficiency as defined by the following claims.

15 20 I claim:

1. A suction cleaner agitator comprising spaced end members, means to rotatably support said end members and means maintaining said end members in fixed relation comprising a smooth beater element.
2. A suction cleaner agitator comprising spaced end plates, means to rotatably support said end plates and means maintaining said end plates in fixed relative relation comprising cylindrical helically-extending beater elements.
3. A suction cleaner agitator comprising spaced end plates, means to rotatably support said end plates, said end plates being connected only by cylindrical beater bars.
4. A suction cleaner agitator comprising spaced end members, means to rotatably support said end members, said end members being connected solely by rounded bars of small 40 cross section spaced radially from the axis of said supporting means to function as beater bars.
5. A suction cleaner agitator comprising spaced circular end plates, means to rotatably support said end plates and rigid beater bars extending between said end plates and connected to the peripheries thereof, said end plates being unconnected save by said bars.
6. A suction cleaner agitator comprising end plates, means to rotatably support said end plates, beater bars connecting said end plates, and means to receive a rotating force, said means comprising a pulley formed in one of said end plates.
7. A suction cleaner rotary agitator comprising rigid beater bars spaced radially from the longitudinal axis of rotation, members connected to and extended from said bars toward said longitudinal axis, means to 50 rotatably support said members and means carried by one of said members to receive a rotating force, said agitator characterized by the fact that said beater bars comprise the only part of said agitator between said members.

8. A suction cleaner rotary agitator comprising rigid beater bars spaced radially from the longitudinal axis of rotation, means connected to and extended from said bars toward said axis, second means to rotatably support said first mentioned means, and means carried by said bars between their ends to receive a rotating force, said agitator characterized by the fact that only said beater bars extend between said supporting means. 75

Signed at Chicago, in the county of Cook, and State of Illinois, the 25th day of October, A. D. 1929.

WILLIS F. HUDSON.
